UNITED STATES PATENT OFFICE.

JOHN PARTMANN, OF NEW YORK, N. Y.

SEWING-MACHINE.

1,331,078.

Specification of Letters Patent. Patented Feb. 17, 1920.

Application filed June 18, 1918. Serial No. 240,654.

To all whom it may concern:

Be it known that I, JOHN PARTMANN, a subject of the Emperor of Austria-Hungary, and a resident of New York city, borough 5 of Manhattan, in the county of New York and State of New York, have invented a new and Improved Sewing-Machine, of which the following is a full, clear, and exact description.

- 10 My invention has for its object to provide a sewing machine, simple in construction and operation which is adjustable to make a straight or a zigzag stitch, as desired.
- 15 Additional objects of the invention will appear in the following specification in which the preferred form of my invention is described.

In the drawings similar reference characters refer to similar parts in all the views, in which—

Figure 1 is a side elevation of my sewing machine.

Fig. 2 is a plan view of Fig. 1.

25 Fig. 3 is a fragmentary sectional elevation showing the construction.

Fig. 4 is a sectional view on the line 4—4 of Fig. 3.

30 Fig. 5 is a fragmentary sectional view illustrating the means for adjusting the throw of the link operating the needle bar frame.

Fig. 6 is an enlarged sectional view on the line 6—6 of Fig. 5.

35 By referring to the drawings, it will be seen that the sewing machine is provided with a frame 10 having a bearing 11 in which there is journaled a main shaft 12, a bevel gear 13 being secured to the shaft 12 and meshing with a bevel gear 14 on a shaft 15 journaled in a bearing 16 in the main frame.

40 Mounted on the shaft 15 and secured for rotating therewith, there is a collar 17 having a transverse guideway 18 in which there is disposed a guide 19 on a base 20 of a spindle 21. There is a stop 17^a on the collar 17 to limit the movement of the base 20 of the spindle 21 in one direction. The spindle 50 21 is journaled in a bearing 22 on a laterally extending arm 23, there being a threaded orifice 24 in the end of the arm 23 in which meshes a screw 25, the said screw 25 being disposed through an orifice 26 in an eccentric 27. Straps 28 are disposed around the eccentric 27 and are secured to an end 29 of

a link 30. The other arm of the link 30 is articulated at 31 to an arm 32 of a needle bar frame 33, which is pivoted at 34 to the main frame 10.

55 It will be understood that when the spindle 21 is co-axial with the shaft 15, rotation of the main shaft 12 will not operate the arm 23 to move the needle bar frame by means of the link 30, but that when the base 20 of the spindle 21 is moved to a position where the spindle 21 is eccentric relatively to the shaft 15 and is secured in this position by means of the set screw 35, which is disposed in a threaded orifice 36 in the collar 17 and which 60 engages the guide 19 on the base 20, that with the rotation of the main shaft 12, the spindle 21 will be given a rotary movement which will reciprocate the link 30 and rock the needle bar frame 33 on its pivot 34.

65 When this rocking movement of the needle bar frame 33 is to be increased, the screw 25 is turned slightly to permit of the rotation of the eccentric 27 relatively to the arm 23. The screws 37 which hold the 70 straps 28 in position are turned when the eccentric may be rotated on the screw 25 and relatively to the arm 23, so that the link 30 may be moved from the full lines shown in Fig. 5 to the dotted lines shown in the 75 said figure, and without rotating the spindle 21.

80 When the correct adjustment has been obtained, the screws 37 and 25 are turned home. Fulcrumed at 38 to the main frame 90 10, there is a lever 39, to the arm 40 of which there is articulated a bent link 41 which is secured in adjusted position to the needle bar frame 33, by means of a bolt 42 which is disposed through an orifice in the 95 bent link 41 and which extends through a slot 43 in the arm 32 of the needle bar frame 33. The bent link 41 may be adjusted relatively to the arm 32 by moving the bolt 42 as may be desired in the slot 43. The other 100 arm 44 of the lever 39 is connected with an arm 45 by means of a link 46, the said arm 45 being secured to a rod 47 which is slidable in bearings 48 on the main frame 10. The main shaft 12 has a longitudinal slot 49 105 in which is slidably disposed a key or member 50 to which is secured a disk 51. The said disk 51 has an opening through which the shaft 12 is disposed. Disposed at the sides of the disk 51 there are disks 52 which 110 are mounted on a base 53 which is secured for movement with the rod 47.

The looper 54 is carried by the key or member 50, and it will be seen that while it will rotate with the shaft 12, it will also be reciprocated when the spindle 21 is eccentric 5 relatively to the shaft 15. The disks 52 carry a bed plate member 55 which slides in a slot in the bed plate 56 and which is provided with an orifice 57 through which the needle 58 may move. The said needle 58 is 10 carried by a needle bar 59, slideable in bearings 60 in the needle bar frame 33. The needle bar 59 is connected with the needle bar lever 61 by a link 62 and the needle bar lever 61 is pivoted to the main frame 10 at 15 63. This needle bar lever 61 is rocked in the usual manner by a link 64 articulated at one end to an arm of the needle bar lever 61 and connected by a strap 65 with an eccentric which is mounted on the main shaft 12 20 at 66.

It will be seen that the needle bar 39 is reciprocated and the looper 54 is rotated by the rotation of the main shaft 12 and independently of the means which are provided 25 for rocking the needle bar frame 33 and for reciprocating the looper 54, and, therefore, the sewing machine may be used in the usual manner for sewing a straight stitch, and, when desired, the spindle 21 may be moved 30 to a position eccentric relatively to the shaft 15 which will rock the needle bar frame 33 by means of the link 30, and with this rocking movement of the needle bar frame 33, the looper 54 and the bed plate member 55 35 will be reciprocated by means of the link 41, the lever 39, the link 46, the rod 47 and the disk 52.

As a convenient means for moving the spindle 21 to an eccentric position relatively 40 to the shaft 15, I provide a lever 67 which is pivoted to the main frame 16 at 68, this lever 67 being disposed in a slot 69 in the rod 47 and articulated in the said slot by means of a pin 70 which is secured in orifices in the rod 47 and which serves as a pointer to 45 determine the relative position of the rod 47. Marks 71 are made on the main frame 10 to assist in determining this position of the rod. As the rod 47 is connected by the 50 means which have been described with the spindle 21, the distance that the said spindle 21 is moved laterally relatively to the shaft 15 may be determined by the movement of the pin 70 relatively to the marks 71 on the 55 main frame 10. To assist in the movement of the spindle to a position eccentric relatively to the shaft 15, the shaft 15 may be rotated slightly.

The feeder 72 is of the usual construction 60 and is operated through the main shaft 12 in the usual manner.

The zigzag stitch referred to in the specification is a cross stitch such as may be used advantageously in the stitching together of 65 straw, braid or other materials and for sew-

ing binding wire to hats. However, it will of course be understood that the zigzag stitch referred to may be used for other purposes.

Having thus described my invention, I claim as new and desire to secure by Letters 70 Patent:

1. In a sewing machine, a main frame, a main horizontal shaft journaled in bearings in the main frame, a vertical shaft journaled in bearings in the main frame, means by 75 which the vertical shaft is operable by the first shaft, an eccentric on the second shaft, a needle bar frame pivoted on a transverse axis on the main frame, a reciprocating looper, and means operable by the eccentric 80 to move the needle bar frame relatively to the main frame and to reciprocate the looper.

2. In a sewing machine, a main frame, a main shaft journaled in bearings in the main frame, a second shaft journaled in the main 85 frame and having a transverse groove, means by which the second shaft is rotated by the first shaft, a spindle with a base having a transverse member slideable in the transverse groove, means to secure the spindle at its 90 base in adjusted position relatively to the second shaft, a needle bar frame movably mounted on the main frame, a reciprocating looper keyed to the main shaft, and means operable by the spindle when it is eccentric 95 relatively to the second shaft to move the needle bar frame relatively to the main frame and to reciprocate the looper on the main shaft synchronously.

3. In a sewing machine, a main frame, a 100 main shaft journaled in the main frame, a second shaft journaled in the main frame and rotatable by the main shaft, a spindle adjustable radially of the axis of the second shaft, means to secure the spindle in adjusted 105 position, a needle bar frame movably mounted on the main frame, a reciprocating looper, means operable by the spindle when it is eccentric relatively to the second shaft to move the needle bar frame relatively to the main frame and to move the looper into operative position relatively to the needle bar frame, a needle bar slideably mounted in the needle bar frame, and means by which the main shaft is adapted to operate the 110 needle bar and to operate the looper.

4. In a sewing machine, a main frame, a shaft journaled in the main frame, a spindle adjustable radially of the axis of the shaft, means to secure the spindle to the 120 shaft in adjusted position, a needle bar frame movably mounted on the main frame, a looper mounted for synchronous movement with the needle bar frame, a needle bar slideable in the needle bar frame, means operable by the spindle when it is eccentric 125 relatively to the shaft to move the needle bar frame relatively to the main frame and to move the looper synchronously therewith, and means to move the needle bar in the 130

needle bar frame and to move the looper synchronously therewith.

5. In a sewing machine, a main frame, a main shaft journaled in the main frame, a second shaft, means by which the second shaft is driven by the first shaft, a spindle adjustable radially relatively to the second shaft, means to secure the spindle in adjusted position, a needle bar frame mov-
10 ably mounted on the main frame, a looper keyed to the main shaft and slidable longitudinally thereof, a needle bar slidable in the needle bar frame, means operable by the spindle when it is eccentric relatively to the second shaft to move the needle bar frame relatively to the main frame and to slide the looper on the main shaft, and means to operate the needle bar in the needle bar frame.

20 6. In a sewing machine, a main frame, a shaft journaled in the main frame, a spindle adjustable radially of the axis of the shaft, means to secure the spindle to the shaft in adjusted position, a needle bar frame movably mounted on the main frame, a looper, a rod slidable in bearings in the main frame, means connecting the rod with the looper for moving the latter synchronously with the needle bar frame, a needle-
25 bar slidable in the needle bar frame, means operable by the spindle when it is eccentric relatively to the shaft to move the needle bar frame relatively to the main frame and to move the rod longitudinally, and means to
30 move the needle bar in the needle bar frame and to operate the looper.

35

7. In a sewing machine, a main frame, a shaft journaled in the main frame, a spindle adjustable radially of the axis of the shaft, 40 means to secure the spindle to the shaft in adjusted position, a needle bar frame movably mounted on the main frame, a looper, a rod slideable in bearings in the main frame, means connecting the rod with the looper 45 for moving the latter synchronously with the needle bar frame, a needle bar slideable in the needle bar frame, means operable by the spindle when it is eccentric relatively to the shaft to move the needle bar frame 50 relatively to the main frame and to move the rod longitudinally, means to move the needle bar in the needle bar frame and to operate the looper, and a lever pivoted to the main frame and articulated to the rod.

55 8. In a sewing machine, a main frame, a
shaft journaled in the main frame, a spindle
adjustable radially of the axis of the
shaft, means to secure the spindle to the
shaft in adjusted position, a needle bar
60 frame movably mounted on the main frame,
a needle bar for movement in the needle bar
frame, a looper mounted for synchronous
movement with the needle bar frame, an arm
having a bearing in which the spindle is
65 disposed, a link connecting the arm with the

needle bar frame for operating the latter, means connecting the needle bar frame with the looper for moving the latter synchronously with the needle bar frame, and means to move the needle bar in the needle bar frame and to move the looper to coöperate therewith. 70

9. In a sewing machine, a main frame, a shaft journaled in the main frame, a spindle adjustable radially of the axis of the shaft, 75 means to secure the spindle to the shaft in adjusted position, a needle bar frame movably mounted on the main frame, a looper mounted for coöperative movement with the needle bar frame, a needle bar slidable in 80 the needle bar frame, means operable by the spindle when it is eccentric relatively to the shaft to move the needle bar frame relatively to the main frame, a lever pivoted to the main frame, a link connecting one 85 arm of the lever with the needle bar frame, a rod slidable in bearings in the main frame, means mounted on the rod for moving the looper synchronously with the needle bar frame, a link connecting the other arm of 90 the lever with the rod, and means to move the needle bar in the needle bar frame and to move the looper to coöperate therewith.

10. In a sewing machine, a main frame, a main shaft journaled in the main frame, a second shaft, means by which the second shaft is driven by the first shaft, a spindle adjustable radially relatively to the second shaft, means to secure the spindle in adjusted position, a needle bar frame movably mounted on the main frame, a looper keyed to the main shaft and slidably longitudinally thereof, a needle bar slidably disposed in the needle bar frame, means operable by the spindle when it is eccentric relatively to the second shaft to move the needle bar frame relatively to the main frame, a lever pivoted to the main frame, a link connecting one arm of the lever with the needle bar frame, a rod slidable in bearings in the main frame, means mounted on the rod for moving the looper longitudinally of the main shaft, a link connecting the other arm of the lever with the rod, and means operable by the main shaft for moving the needle bar in the needle bar frame. 115

11. In a sewing machine, a main frame, a main shaft journaled in the main frame, a second shaft, means by which the second shaft is driven by the first shaft, a spindle 120
adjustable radially relatively to the second shaft, means to secure the spindle in adjusted position, a needle bar frame movably mounted on the main frame, a looper keyed to the main shaft and slidable longitudinally 125 thereof, a needle bar slidably disposed in the needle bar frame, means operable by the spindle when it is eccentric relatively to the second shaft to move the needle bar frame relatively to the main frame, a lever pivoted 130

to the main frame, a link connecting one arm of the lever with the needle bar frame, a rod slidable in bearings in the main frame, means mounted on the rod for moving the 5 looper longitudinally of the main shaft, a link connecting the other arm of the lever with the rod, means operable by the main shaft for moving the needle bar in the needle bar frame, and a lever pivoted to the 10 main frame and articulated to the rod.

12. In a sewing machine, a main frame, a shaft journaled in the main frame, a spindle adjustable radially of the axis of the shaft, means to secure the spindle to the shaft in 15 adjusted position, an arm having a bearing in which the spindle is journaled, an eccentric rotatably mounted on the arm, means to secure the eccentric to the arm in adjusted position, a needle bar frame movably 20 mounted on the main frame, a looper mounted for synchronous movement with the needle bar frame, a needle bar slidable in the needle bar frame, a link having a strap at one end secured around the eccentric 25 and with its other end articulated to the needle bar frame, means to move the looper synchronously with the needle bar frame, and means to move the needle bar in the needle far frame and the looper to coöperate 30 therewith.

13. In a sewing machine, a main frame, a shaft journaled in the main frame, a spindle adjustable radially of the axis of the shaft, means to secure the spindle to the shaft in 35 adjusted position, a needle bar frame movably mounted on the main frame, a looper mounted for synchronous movement with the needle bar frame, a needle bar slidable

in the needle bar frame, means operable by the spindle when it is eccentric relatively to 40 the shaft to move the needle bar frame relatively to the main frame, and means to move the needle bar in the needle bar frame and to move the looper for coöperating therewith. 45

14. In a sewing machine, a main frame, a shaft journaled in the main frame, a spindle adjustable radially of the axis of the shaft, means to secure the spindle to the shaft in adjusted position, a needle bar frame movably 50 mounted on the main frame, a looper inounted for synchronous movement with the needle bar frame, a bed plate section having an orifice for the needle and mounted for synchronous movement with the needle 55 bar frame and the looper, a needle bar slidable in the needle bar frame, means operable by the spindle when it is eccentric relatively to the shaft to move the needle bar frame relatively to the main frame and to move 60 the looper and the bed plate section synchronously therewith, and means to move the needle bar in the needle bar frame and to operate the looper for coöperating with the needle bar. 65

15. In a sewing machine a shaft having an eccentric, a needle bar frame pivoted on a horizontal axis, an arm having a bearing in which the eccentric is disposed, a link connecting the arm with the needle bar 70 frame for operating the latter, looping means for coöperating with a needle movably mounted in the needle bar frame, and means operable by the needle bar frame for actuating the looper.

JOHN PARTMANN.
